TIE NIPPER

Wade E. Haist, Aurora, Ill., and Pernal F. Thomas, La Crosse, Wis.

Application January 16, 1941, Serial No. 374,782

5 Claims. (Cl. 254—131)

This invention relates to devices designed to facilitate the raising and holding in raised position of heavy objects, and pertains particularly to a tool for raising and supporting railway ties.

In the maintenance of railroads, it is necessary from time to time to remove old cross-ties and put in new ones, and the present practice requires the services of three men. After the new tie is pulled in and placed loosely under the rails, one man uses a bar as a pry by placing one end of the bar under the tie and resting the bar upon a suitable fulcrum so as to effect the lifting of the tie against the under side of the rail. While the one man is maintaining the tie in raised position against the bottom of the rail, this procedure being termed "tie nipping," the other two men employ spike mauls to drive new spikes into the tie.

The tool or device embodying the present invention is designed to raise and hold the tie against the rail without requiring the services of a third man, the tool functioning, after it has been placed under the end of the tie and properly manipulated to bring the tie into position against the under side of the rail, to maintain the tie in such position without further attention.

Another object of the invention is to provide a "tie nipping" tool which is of simple construction and which to a certain extent operates automatically to establish a locking grip upon the tie after the latter has been raised to position whereby the tool will function to maintain the tie raised, as stated.

A further object is to provide a relatively simple but strong and durable lifting and supporting tool of the character stated, which may be readily employed in any situation where a workman finds it necessary to raise and maintain in a desired raised position any object upon which he is working.

The invention will be best understood from a consideration of the following detailed description taken in connection with the accompanying drawing, it being understood, however, that the invention is not to be considered as limited by the specific illustration or description, but that such illustration and description constitutes a preferred embodiment of the invention.

In the drawing:

Fig. 1 is a view in side elevation of the tool embodying the invention showing the same in use.

Fig. 2 is a sectional view on the line 2—2 of Fig. 1.

Fig. 3 is a view in plan of the forward end of the handle bar per se.

Fig. 4 is a plan view of the forward end of the brace arm per se.

Referring now more particularly to the drawing, the numeral 1 designates the handle bar of the tool which, as shown, is formed from a single length of bar material, preferably, although not necessarily, of T-form.

At one end of the bar a short portion is offset to form the handle 2. This offset of the handle is above the center line of the bar as considered when the bar is in horizontal working position and it permits of the more easy use of the tool for the reason that the workman operating the device will not be required to stoop so low as would be the case if the bar were straight to its rear end. In addition, in multiple track territory, this offsetting of the handle will prevent this end of the bar from coming in contact with gravel on the parallel track.

At the other or forward end of the bar 1 there is formed the downwardly projecting foot 3 which is here shown as being in the form of an open frame which projects from the center of the bar in the opposite direction of the offset handle 2. This foot, of course, is upon the under side of the bar when the latter is in operating position, and it is provided with a relatively long under face or sole 4 which extends in the direction of the length of the bar. Integral with the sole is a spur or tooth 5 which extends transversely thereof, the function of which will be to bite into the underlying surface to offset any tendency of the sole to slip when the tool is in operative position.

The forward side of the foot extends obliquely of the bar and forwardly, as indicated at 6, merging into a relatively broad sharpened Jaw 7, the width of which extends transversely of the bar. The edge of this jaw is preferably toothed, as indicated at 8, to facilitate the biting of the jaw into the body being lifted.

The top face of the jaw 7 is indicated by the numeral 9 and, as shown in Fig. 1, this face extends obliquely forwardly with respect to the length of the handle, the edge of the jaw being in a plane above the top of the handle bar. By turning down the forward end of the handle bar, as indicated at 10, it will be seen that a relatively long upper surface is provided for the jaw, thus permitting the sharpened edge of the jaw to be easily inserted beneath an object which lies close to the ground or another supporting surface. The jaw thus forms with the forward end of the handle bar a substantially V-shaped

pocket in which an edge of the object to be lifted may be located prior to the performance of the lifting operation.

Rearwardly from the head 3 the handle bar is of slightly increased width, as indicated at 11, and extending transversely through this widened portion is a pivot pin 12.

The numeral 13 designates a brace arm which at its rear end is forked or bifurcated, each of the furcations being indicated by the numeral 14, to straddle the portion 11 of the handle bar. Upon the inner face of each furcation 14, a lug or shoulder 15 is formed to contact the side faces of the web portion of the bar when the same is of T-formation as shown, so as to establish a firm contact between the ends of the furcations and the sides of the handle bar. The furcations are provided with suitable apertures 16 which pass through the shoulders 15 and these are aligned with a suitable passage 17 formed through the handle bar to receive the pivot bolt or pin 12 in the manner shown. In this manner the brace arm 13 is pivotally coupled with the bar.

At its free or forward end the brace arm is broadened to form, or has secured thereto, a relatively wide jaw 18 which is longitudinally curved slightly, as shown, toward the fixed jaw 7. This movable or bracing jaw may be toothed along its free sharp edge, as indicated at 19, so as to obtain a good bite into the object upon which the "nipper" is used.

The pivot bolt 12 extends transversely of the bar, as shown, and thus the jaws may be moved together for cooperative action, as will be readily seen, this cooperative action being facilitated by the fact that the jaws are arranged so that their sharpened or toothed edges are in convergent relation, particularly when the bracing arm is moved or swung down toward the handle bar.

The disposition of the arm 13 upon the handle bar is such that when the jaws are swung entirely together, the toothed edge of the bracing jaw 18 will over-reach or extend slightly beyond the toothed edge of the fixed jaw 7. Thus when the handle bar is horizontally disposed, when in use, the toothed edges of the jaws may be made to occupy a position in the same vertical plane or a plane which is perpendicular to the handle bar.

In the use of the present implement the arm 13 is first thrown back away from the forward end of the handle bar and the fixed jaw 7 is inserted beneath the tie or other object to be lifted. In Fig. 1 the tie is shown engaged by the tool and the tie is indicated by the numeral 20. The outer end or handle end 2 of the bar 1 is then forced downwardly, the bar pivoting or fulcruming on the sole 4, or if the foot is upon a hard surface, upon the spur 5. In this manner it will be seen that the tie or other object will be lifted from the ground or supporting surface. After the edge of the fixed tooth has been engaged beneath the object, the brace arm may be swung forwardly to bring the bracing jaw into position against the adjacent side of the object and thus when the handle bar is swung downwardly and the object lifted, the toothed edge of the bracing jaw 18 will slide down the said adjacent surface of the object. When the object has been raised to the desired height, the downward pressure can be released from the handle bar and the weight of the object will tend to cause the foot to rock back to its initial position and this will cause the toothed edge of the bracing jaw to bite into the surface of the object.

and hold it from returning to its former position, thus maintaining the object supported by the foot of the tool in the manner illustrated in Fig. 1.

5 While the "nipper" has been illustrated and described in connection with a railway tie, it will be readily apparent that it may be used for various other purposes as, for example, by a carpenter for maintaining a door in a desired raised position while fitting and applying hinges, and for other similar purposes. It will be readily recognized that various other uses may be made of the tool besides the ones particularly referred to.

15 What is claimed is:

1. An implement of the character stated, comprising a handle bar, said bar having a portion at one end offset from its longitudinal center to provide a handle, means integral with the bar at its other end and extending from the longitudinal center in the opposite direction from the direction of offset for the handle, providing a fulcrum foot, said fulcrum foot having a sole surface extending lengthwise of the bar, an obliquely directed jaw extending from the end of the bar adjacent the fulcrum foot and away from the foot, a bracing arm pivotally coupled with the bar rearwardly from said foot and having a jaw at its free end, said jaw being slightly arcuately curved and being movable toward the first jaw for cooperative action therewith, and a spur extending across the sole of said foot.

2. An implement of the character stated, comprising a handle bar, said bar having a portion at one end offset from its longitudinal center to provide a handle, means integral with the bar at its other end and extending from the longitudinal center in the opposite direction from the direction of offset for the handle, providing a fulcrum foot, said fulcrum foot having a sole surface extending lengthwise of the bar, a jaw forming an extension of said fulcrum foot and directed obliquely from the forward end of the bar, said fulcrum foot having a forward side merging with one face of the jaw and extending obliquely with respect to the handle bar, the jaw having an upper face coacting with an angular forward end portion of the handle bar to form a substantially V-shaped recess across the handle bar behind the jaw, a bracing arm pivotally coupled with the handle bar for oscillation upon an axis extending transversely thereof, said axis being located rearwardly of the foot, and a jaw formed at the free end of said bracing arm for cooperative action with said first jaw.

3. A device for lifting an object at one side while the opposite side is resting on a supporting surface and maintaining said one side lifted, comprising an elongated body, means at one end of the body for engagement under the object, means connected with the body forming a supporting fulcrum adjacent to the object engaging means, a rigid arm pivotally coupled at one end to the body at the side of the fulcrum remote from the object engaging means, and means at the other end of the arm formed to bear against the said one side of the object, one of the last mentioned two means having a substantial width extending across the body by which side rocking of the body is prevented, the arm forming a bridge across the angle between the body and the said one side of the object whereby when the said one side of the object is lifted by oscillation of the body on the fulcrum while the said arm means is against the object the arm will hold

the body against reverse oscillation without continual manual effort.

4. A device for lifting an object at one side while the opposite side is resting on a supporting surface and maintaining said one side lifted, comprising a bar, a jaw at one end for engagement under the object to be lifted, a fulcrum foot carried by the bar adjacent the jaw, a rigid arm pivotally attached at one end to the bar, a relatively broad bracing jaw at the other end of the arm having a portion directed longitudinally of the arm for contact with the said one side of the object, the arm being adapted to be disposed as a bracing bridging means across the angle between the bar and the said one side of the object when the bracing jaw is against said one side whereby the force of the weight of the object on the first jaw tending to reversely oscillate the bar after its oscillation on the fulcrum to raise the object, is transmitted through the arm to the bar at the side of the fulcrum remote from the first jaw to hold the bar and object against reverse oscillation without continual manual effort, the breadth of the bracing jaw assisting in stabilizing the device against side rocking.

5. A device for lifting an object at one side while the opposite side is resting on a supporting surface and maintaining said side lifted, comprising a bar, means at an end of the bar for engaging beneath the object adjacent said one side, means forming a fulcrum foot adjacent the first means facilitating rocking the other end of the bar downward in a vertical plane to raise the object, a rigid arm straight throughout substantially its entire length and having one end pivotally attached to the bar at a materially greater distance from the object engaging means than the distance lengthwise of the bar between the fulcrum and the object engaging means, and means carried at the other end of the arm for establishing a firm non-slipping engagement with the said one side of the object whereby the force of the weight of the raised object tending to reversely rock the bar will be transmitted by the arm to the bar at the side of the fulcrum away from the object to hold the other end of the arm down without continual manual effort.
